UNITED STATES PATENT OFFICE.

JOHN J. McNALLY, OF CALIFORNIA, MISSOURI.

TELEPHONE SYSTEM.

SPECIFICATION forming part of Letters Patent No. 511,739, dated December 26, 1893,

Application filed August 31, 1893. Serial No. 484,504. (No model.)

To all whom it may concern:

Be it known that I, JOHN J. McNALLY, a citizen of the United States, residing at California, in the county of Moniteau and State 5 of Missouri, have invented certain new and useful Improvements in Systems of and Apparatus for Operating Telephone and Telegraph Lines; and I do hereby declare the following to be a full, clear, and exact description of the 10 invention, such as will enable others skilled in the art to which it appertains to make and use the same.

My invention relates to improvements in systems of and apparatus for operating telephone and telegraph lines, and it has for its 15 object to automatically make the connections between one station and another.

The invention will first be described in connection with the accompanying drawings, and 20 then particularly pointed out in the claim.

In the drawings—Figure 1 is a diagrammatic view of a system with two offices embodying my invention. Fig. 2 is a front elevation of the mechanism which is used for 25 each office. Fig. 3 is a central vertical section of the indicator. Fig. 4 is a side view illustrating the construction of the local switch.

Referring to the drawings, A is a central 30 station, while B, and C are offices. These offices are connected to each other through the two main circuits E and F, one of which, (E) I will designate the indicator circuit, while the other (F) is the instrument circuit, the 35 term instrument referring to either a telephone, telegraph or other similar device.

G is a main battery serving to energize both circuits and connected as shown.

In each station or office is located an indicator 40 1, a telephone or telegraph instrument 2, a bell call 3, a circuit-breaker 4, an electro-magnetic switch 5, a local circuit in which the bell is included, and a local battery for energizing the local circuit.

45 In the central office is an electro-magnetic switch which closes the indicator circuit when its magnets are energized, and opens the same circuit when its magnets are de-energized.

50 The operation, broadly considered, is as follows: The indicator circuit is normally open, while the instrument circuit is normally

closed. Any office desiring to call another office opens the instrument circuit which demagnetizes the main electro magnetic switch 55 in the central office, thereby closing the indicator circuit. The indicators in all the offices are included in this indicator circuit and each indicator is provided with an electro-magnetic step-by-step mechanism which rotates its respective indicators, this mechanism being operated by the making and breaking of the indicator circuit through the medium of the circuit breaker in the office which does the calling. The indicators move synchronously step-by-step, at each step indicating a number on a dial, as will be more fully explained hereinafter. When the indicator in the calling office points to the number of the office which it is desired to call, the indicator 60 hand will come in contact with a plug stuck in a perforation in the face of the dial opposite the number of the station called, by which act the instrument circuit is automatically closed, which energizes the main 65 electro magnetic switch in the central office and thereby opens the indicator circuit. At the same time, a local electro-magnetic switch in each office is energized, but these switches have an abortive function in every 70 office except that whose number is shown on the indicator. In the last mentioned office the local electro-magnetic switch closes a local circuit which rings the call bell and indicates to the office that it is called. The telephones 75 or other instruments of both the office calling and the office called may then be switched onto the instrument circuit in the usual way.

The indicator is constructed as follows: On a revoluble axis 6 is fixed a front and a back 80 indicator needle or hand 7 and 8 the front one moving over a front dial 9, while the rear one moves over a rear dial 10. Between the back indicator hand and the front dial is a ratchet-wheel 11 also fixed to the axis. 85 This ratchet-wheel is moved by a pawl-rod 12, moving in guides 13 and provided with a pawl or tooth 14 which engages the teeth of the ratchet-wheel. The upper end of the pawl-rod is pivotally attached to one 90 end of a lever 15, pivoted at 16, and carrying an armature 17, adapted to be drawn down by electro-magnets 18, which are included in the indicator circuit. The down-

ward movement of the armature of course also draws down the lever and the pawl-rod, and to raise them again a spring 19 is provided, being attached at one end to an arm 5 20 projecting downward from the lever and at the other end to a post 21. The tension of the spring is adjustable in a well-known manner by means of a screw 22 and nut 23. The play of the lever is also adjustable by 10 means of screws 24 and 25 as will be fully understood from the drawings.

It is plain that as the indicator circuit is made and broken, the electro-magnets will draw the lever and pawl-rod down, while the 15 spring will force it up, thereby rotating the ratchet-wheel one tooth each time, and as numbers on the front dial correspond to the teeth on the ratchet-wheel, the front indicator hand will move over the front dial one number at a time. To prevent the momentum of the rotating ratchet-wheel from carrying it 20 too far, a leaf spring 26 is secured to the dial and bears against a flange 27 formed integral with the ratchet-wheel and having flattened 25 surfaces as shown at 28.

To interrupt the indicator circuit and thereby actuate the step-by-step mechanism, a circuit-breaker is provided in each office, as before stated, this consisting, preferably, of a 30 gear-wheel 29 rotated by a pinion 30 and crank 31. To one side of the gear-wheel and preferably integral therewith is a cam-disk 32 provided with a series of cams 33, which are arranged to engage the end of a spring 34 35 and force it away from a contact point 35, the contact point and the spring being included in the indicator circuit.

It is plain that by turning the crank 31 the circuit will be opened and closed the spring 34 40 normally resting against the contact point 35.

On the back dial of each indicator are located two studs or posts 36 and 37 included in the instrument circuit, as shown, Fig. 1, the position of these studs on the back dial 45 being different for each indicator on the line. For instance, in an office to which, say the number 3 was assigned, the studs or posts would be directly below the number 3 on the front dial, while office number 4 would have 50 the studs below the number 4 of the front dial, &c. One of the studs 36 is connected by a wire 38 to one pole 39 of a plug cut-out, the other pole 40, of which is connected by a wire 41 to the other stud, 37, and pole 39 is 55 also connected to the front indicator hand, as will be fully understood from the drawings. A telephone or telegraph instrument 2 is included in the branch circuit formed by wire 41. The front dial is provided with a series 60 of holes corresponding to the numbers on the dial and adapted to receive a plug 42 which is normally located in the plug-opening between the two poles 39 and 40 of the plug-cut-out and serves to make a connection between such poles. This plug is connected by 65 a flexible wire to the pole 40 of the cut-out, so that when placed in any desired hole of

the dial as shown in dotted line in Fig. 1 and struck by the front hand of the indicator it serves to close the instrument circuit which 70 has been opened by the removal of such plug from the cut-out. Immediately opposite the two studs 36 and 37 is placed an electro-magnetic switch included in the instrument circuit and constructed similar to an ordinary 75 telegraph sounder, being provided at the end of its armature lever 43, with a pair of teeth or contact points, 44 and 45, insulated from each other and from the lever. These teeth or points are included in a local circuit 46 in 80 which a call bell 47 and a local battery 48 are included. The end of the armature lever of this local circuit switch is of such size that it will enter snugly between the two studs 36 and 37 and will make a contact between them. 85 To prevent this taking place when not desired, an insulating plug 49 as seen in Fig. 4 is arranged to be inserted in the space between such studs 36 and 37 by the office calling. It is plain that when the local circuit 90 switch is magnetized by the closing of the instrument circuit it will have its lever drawn down between the studs 36 and 37 and will then cut out the telephone of its own office. But the office calling, having already inserted 95 the insulating plug 49 between the two studs will not have its telephone cut out, and the rear indicator needle or hand of the office called will then be directly over the two studs of the indicator, and consequently its telephone cannot be cut out by its local switch. As soon as the local switch, of the office called, is magnetized by the closing of the instrument circuit at the calling office (which, as 100 before stated, is done by the front indicator 105 needle striking the plug resting in the hole opposite the number of the office to be called) the contact points 44 and 45 are connected by contacting with the metallic rear hand of the indicator and the local circuit at the office called is thereby closed, thus ringing the call-bell. A suitable switch 50 placed convenient to the telephone permits the operator at the office called to cut out his bell temporarily, and this switch may either be operated by 110 the hanging up or removing of the receiver of the telephone or by a spring push-button so that it will be impossible for the operator to leave the call bell cut out by accident.

The electro-magnetic switch in the central office is constructed similar to an ordinary telegraph sounder, and is provided at the end of its armature lever with a tapered plug 51 which enters the opening between the two poles 52 and 53 of a plug cut-out included in 115 the indicator circuit. A spring 54 serves to draw the armature-lever upward so as to close the indicator circuit, while the energizing of the electro-magnets draws the lever down and holds it down so long as the instrument circuit is closed. 120

When the operator at the office calling has done talking, he removes the plug 42 from its position opposite the number of the office to

which he has been talking and places the said plug in the hole opposite zero; by then turning the crank of the circuit-breaker, the indicators are all moved around to zero. The 5 plug 42 is then removed from the hole at zero and inserted in its normal place between the poles 39 and 40 of the cutout. A solid plug is then placed in the hole at zero in contact with the front indicator hand.

10 Having thus fully described my invention, what I claim as new, and desire to secure by Letters Patent, is—

In a system for operating telephones and similar instruments, the combination with a 15 normally open indicator circuit, a normally closed instrument circuit, means for energizing both circuits, an electro-magnetic switch arranged to open the indicator circuit on the closing of the instrument circuit, a circuit breaker for each office included in the indicator circuit, an indicator in each office provided with a front dial, a back dial, a front and back needle, and a step-by-step device included in the indicator circuit and operating 20 the needles, a plug cut-out in each office 25

and included in the instrument circuit, a plug connected to one of the poles of the cut-out and insertible in the front dial in the path of the front needle, a wire connecting the other pole of the cut-out to the front needle, a pair of studs 30 included in the instrument circuit, a local electro-magnetic switch included in the instrument circuit, and provided with a lever arranged to connect the two studs, and with two contact points arranged to engage the back 35 needle of the indicator when the latter is in line with the lever, a local circuit ending at the contact points on the lever, a bell included in the local circuit, means for energizing the local circuit, and a series of telephones 40 included in the instrument circuit and arranged to be cut out by the entry of the lever of the local switch between the two studs, substantially as described.

In testimony whereof I affix my signature in 45 presence of two witnesses.

JOHN J. McNALLY.
